UNITED STATES PATENT OFFICE.

LE GRAND PARISH, OF NEW YORK, N. Y., ASSIGNEE, BY MESNE ASSIGNMENTS, TO
AMERICAN ARCH COMPANY, OF NEW YORK, N. Y., A CORPORATION OF DELAWARE.

LOCOMOTIVE-BOILER FIRE-BOX.

1,138,062.

Specification of Letters Patent.

Patented May 4, 1915.

Application filed October 1, 1913. Serial No. 702,835.

To all whom it may concern:

Be it known that I, LE GRAND PARISH, a citizen of the United States, and a resident of New York city, county of New York, and 5 State of New York, have invented certain new and useful Improvements in Locomotive-Boiler Fire-Boxes, of which the following is a specification.

My invention relates to improvements in 10 locomotives and has particular reference to improvements in the fireboxes of locomotive boilers.

The object of my invention is to increase 15 the efficiency with which the fuel is consumed in locomotive fireboxes and to decrease the possibility of the escape of sparks and unburned fuel particles from the firebox.

A further object of my invention is to 20 provide a firebox in which a relatively thin and substantially continuous sheet of air shall be injected in the firebox in the path of the rising firebox gases, and through which it shall be necessary for the gases of 25 combustion to penetrate on their way to the flues.

A further object of my invention is to 30 provide means whereby a transverse sheet of heated air shall be injected into the firebox in a substantially horizontal direction and in the path of the rising gases whereby the partly burned gases shall be intermingled and intermixed with the heated air, and the fuel shall be substantially perfectly consumed for the gases escape from 35 the firebox.

My invention consists in a locomotive boiler firebox provided with a transverse vertically extending refractory wall in the 40 forward end thereof and spaced from the flue sheet, said wall being provided with air conduits which rise from the lower end thereof and the upper part of the wall being provided with an air discharge which extends substantially across the firebox and 45 which is adapted to cause the heated air rising through the wall to enter the firebox in a transverse sheet extending from side sheet to side sheet and through which the rising 50 firebox gases have to pass as they rise in the firebox.

My invention also consists in a refractory cross-wall for locomotive fireboxes, which 55 extends across the firebox adjacent to the forward end thereof and provided with an

air inlet or discharge adjacent to its upper end adapted to admit air to the firebox above the fuel bed, the air inlet being formed of a series of narrow elongated slots arranged in a horizontal row and separated by narrow partitions, said inlet being protected from the entrance of slag by an overhanging wall of refractory material. 60

My invention also consists in the several arrangements and combinations of parts 65 and in the features of construction whereby the above and other objects are attained and all as hereinafter described and particularly pointed out in the appended claim.

My invention will be more readily understood by reference to the accompanying drawings forming part of this specification and in which:

Figure 1 is a central, vertical, longitudinal section of the firebox, equipped with a 75 cross-wall, and embodying my invention; Fig. 2 is a vertical, transverse section of the firebox on the line 2-2 of Fig. 1; Fig. 3 is a horizontal section of the firebox on the line 3-3 of Fig. 1; Figs. 4 and 5 are vertical transverse sections showing modified forms of air inlets; Fig. 6 is a horizontal section of the wall on the line 6-6 of Fig. 1; Fig. 7 is a view similar to Fig. 1, showing a modified form of the wall and air outlet. 80

In the art of burning fuels, it is well known that once the fuel has been gasified it is necessary to mix the volatile gases thoroughly with the air in order to produce perfect combustion, and it has been the object of many inventors to provide fireboxes in which this complete and thorough admixture of the gases of combustion with the air will be caused to take place and with more or less success. It is now a general practice to admit air to the firebox from many points through the side walls, the air being drawn into the firebox by reason of the strong artificial draft which is made use of, but this method of supplying air to the 100 firebox does not result in the most efficient burning of the fuel for the reason that the air is not heated to any appreciable extent before coming into contact with the burning gases and the consequence is that the air reduces the temperature of the burning gases and thus slightly retards the combustion thereof. It has also been attempted to admit air into the firebox through a refractory wall, but without very great success, for 105 110

the reason that the outlets of the air passages have either been constructed to admit the air in large volumes or streams at separated points or have been constructed to admit the air in a continuous sheet but through an opening which is unprotected against the entrance of slag. It is my particular object to provide an inlet for the air which will force the air to enter the firebox in a substantially horizontal and continuous thin sheet and which inlet shall be so formed that slag and similar substances cannot obstruct the end of the inlet and consequently the inlet remains indefinitely in the shape in which it is made.

A further feature of my invention is that in providing the air inlet, I preferably arrange it as part of a transverse wall which is placed in the forward part of the firebox spaced rearwardly from the flue sheet and I thus admit the air in a sheet in the firebox in such a relation to the flue sheet that the added air will be thoroughly commingled and mixed with the burning fuel before the firebox gases reach the flue sheet and the separation of the wall from the flue sheet provides an auxiliary combustion chamber in which the burning gases can expand, as they flow to the flues and in expanding will be caused to deposit or drop their burden of cinders or unburned solid fuel particles. These particles collect in the bottom of this auxiliary combustion chamber and are thus prevented from passing into the flues and being forced out of the stack by the strong draft made use of in locomotives at the present time.

For the purpose of introducing the air in a preheated condition I arrange vertical air conduits in conjunction with the wall, opening at the lower ends to the outer air, and through which air can rise to enter the firebox. At the upper part of the wall I arrange a substantially continuous thin slot through which the air, which rises through the conduits, enters the firebox in a substantially horizontal sheet extending from side to side, and I further arrange this narrow slot below an overhanging ledge so that the slot is protected against any fuel particles or slag which might otherwise drop into the slot and obstruct it. I arrange the opening of this slot through the rear face of the wall and consequently the air which enters the firebox through the slot is projected rearwardly in the firebox over the fuel bed, and as all of the gases of combustion have to rise in the firebox and flow forwardly over the top of the wall, the air, which is thus projected rearwardly into the firebox, forms an air baffle through which the rising firebox gases must penetrate and by means whereof the firebox gases and the heated air are most thoroughly intermingled and mixed. Furthermore, as the commingling firebox gases

and air turn in their progress through the firebox to flow over the wall, this mixing of the air and gases is completed and they are in such a condition of admixture and high temperature that, as they reach the auxiliary combustion chamber, which is protected by the wall, they are in the best condition to complete the burning of the gases within this auxiliary combustion chamber before they escape from the firebox through the flues. The cross wall also serves the purpose of preventing the direct flow of the gases of combustion from the fuel bed to the flues, causing them to be retained somewhat in the firebox and forcing them to distribute their heat throughout substantially the whole interior area of the firebox, and particularly to the crown sheet.

A firebox A, as illustrated in the drawings, comprise a flue sheet a^1 at the forward end, side sheets a^2 , a rear sheet a^3 and a crown sheet a^4 . A fuel door or opening a^5 is provided in the rear wall of the firebox and flues a^6 lead forward from the flue sheet. The firebox is provided with a grate a^7 of usual construction. I arrange a transverse refractory wall B in the forward end of the firebox rising from substantially the level of the grate and terminating below the crown sheet. This wall is spaced rearwardly from the flue sheet to provide an auxiliary combustion chamber a^8 between the wall and the flue sheet and a main combustion chamber a^9 between the wall and the rear end of the firebox. These two combustion chambers are connected by the passage a^{10} above the wall B. For supporting the wall in position I provide a transverse bridge member C which extends across the firebox at the level of the grate and is secured at its ends to the lower part of the sides of the firebox by bolts a^{11} . This bridge member serves to support the wall B, and I preferably build the wall of a number of horizontal rows b^1 of bricks b^2 , the bricks b^2 being of such a size that they can be readily placed in position and small enough so that they can be passed through the fire-door a^6 into the firebox. The bridge member is provided with a horizontal bearing plate c^1 at its upper edge which is wide enough to receive the wall and carries at its rear edge a ledge or rib c^2 which helps to hold the wall in position upon the bridge member. For the purpose of retaining the wall in position I provide buck stay plates c^3 which rise in contact with the forward face of the wall and are secured rigidly at their lower ends to the bridge member C. This buck stay plate serves to protect the wall, and, as a further security, I usually bolt the upper row of the bricks of the wall to the upper part of the buck stay plates by means of bolts c^4 . As illustrated in Figs. 1 and 2 I provide the wall with vertically extending

air conduits b^8 and I provide the bridge member C with openings in the plate c^2 registering with the lower ends of these passages and through which air may enter said passages. I complete the wall at its upper edge with a top row of bricks b^4 which are wider than the thickness of the wall and which project from and over the rear face of the wall, forming an over-hanging ledge 5 or coping b^5 , and I provide an inlet b^6 for the air which enters the firebox substantially at the junction of the over-hanging coping b^5 and the rear face of the wall. This inlet thus enters the firebox in such a 10 manner that the air which is projected therethrough enters the firebox in a substantially horizontal direction and is projected through the rising firebox gases. This inlet opening is protected against the entrance of slag 15 or other obstructions by the overhanging coping b^5 .

As shown in Figs. 2 and 6, the inlet b^6 comprises a series of narrow elongated slots b^7 which are continuous from side to side in 20 the firebox and which serve to inject the air in a substantially continuous horizontal sheet. For the purpose of providing this form of inlet I provide in the undersides of the bricks b^4 curved passages b^8 which connect at their 25 inner ends with the upper ends of said air conduits b^8 and the outer ends of which are compressed vertically and elongated horizontally to provide the narrow elongated slots b^7 , before described. The air, in rising 30 through the wall absorbs heat from the wall and consequently it is injected into the firebox in a relatively highly heated condition and thus best serves to increase the effective burning of the fuel. The inlet openings 35 may be described as fan-shaped, in that they change from the substantially compact area of the conduits b^8 to the thin slot outlets b^7 , and the air is consequently caused to enter the box in a substantially thin sheet, but 40 which sheet is divided throughout its extent into a plurality of streams. It will, of course, be understood that these several streams tend to spread as they enter the firebox and that they thus serve to aid in the commingling 45 and intermixing of the gases of combustion. The wall as mentioned before provides an auxiliary combustion chamber in the forward end of the firebox in which the firebox gases can complete their combustion before 50 they escape through the flues. Furthermore, this chamber being very much larger in cross sectional area than the passage a^10 above the wall, serves to permit the gases of combustion to expand and thus reduce their rate of 55 flow to such an extent that any cinders or other solid particles which they may be carrying are deposited in this auxiliary combustion chamber, and for the purpose of conveniently withdrawing any accumulation which 60 may occur in the bottom of the chamber, I

provide this chamber with a cinder outlet or opening D in the lower part which is normally closed by a cover d^2 and through which the accumulation of cinders can be easily withdrawn from time to time. 70

In Figs. 4 and 5 I have illustrated some slight modifications of the inlet nozzle or opening. In Fig. 4 I have shown an inlet which instead of being formed of the relatively thin long slots b^7 , is formed of a number of quite short openings b^9 separated by relatively thin partitions d^9 . The effective result, however, is substantially the same as in the form shown in Fig. 6, that is, the air enters the firebox in substantially a continuous sheet from side to side but the various parts thereof are more finely subdivided and consequently the cross currents induced in the air issuing from this plurality of small nozzles serves to effect the thorough intermingling and intermixing of the air with the firebox gases. In Fig. 5 I have shown still another form of outlet. Instead of the substantially square partitions, b^9 , shown in Fig. 4, I have provided the underside of the bricks b^4 with corrugations b^{11} which provide a series of relatively small inlet openings b^{12} , these openings, together, forming what may be termed a single continuous outlet from side to side adapted to inject the air into the firebox in the form of a substantially continuous sheet, but serving to disturb the individual parts of the sheet in such a manner that the mixing of the air with the firebox gases is enhanced. 90

In Fig. 7 I have shown a form of wall which has some advantages over the form shown in the other drawings. In this form the air conduit, instead of being provided in the wall itself, is provided in the buck stay plates, the bricks of which the wall is composed being solid or non-perforate. The buck stay plate E, illustrated in Fig. 7, rises in contact with the forward face of the wall and is secured at its lower end to the bridge member C. As shown in Fig. 7 the horizontal passage b^{15} is formed partly in the upper brick b^{14} of the wall proper and partly in the topmost brick or coping b^4 . This top row of bricks is substantially identical with the bricks illustrated in Figs. 1 to 3. Consequently the inlet for the air illustrated in Fig. 7 is substantially the same as the inlet illustrated in Fig. 1. It is to be noted that in the form of the invention shown in Fig. 7, the inlet is protected by means of the overhanging ledge b^5 in the same manner as in the form of the invention shown in Fig. 1. Furthermore, as the buck stays E are exposed to the high temperature of the gases in the auxiliary combustion chamber a^6 , they serve to heat the air which rises through the passages c^1 before the air enters the firebox, and, on the other hand, as the rising air extracts heat from the buck stays, it 120 125 130

serves to protect the buck stays against destruction by the high temperatures to which they are exposed.

As many modifications of my invention will readily suggest themselves to one skilled in the art I do not limit or confine my invention to the specific structures herein shown and described.

I claim:

- 10 A locomotive boiler firebox and its grate, in combination with a cross wall in the firebox at the forward end of the grate, said wall being composed of horizontal rows of suitably stayed refractory bricks and extending from side to side of the firebox, a row of
- 15

refractory coping bricks stayed on the top row of wall bricks, said coping bricks overhanging the rear of the wall, and said bricks containing a plurality of air passages terminating in a sub-divided, but substantially 20 continuous, slot at the juncture of the wall and coping.

In testimony whereof I have hereunto set my hand this 19th day of Sept., 1913, in the presence of two subscribing witnesses.

LE GRAND PARISH.

Witnesses:

JOHN P. NEFF,
JOA T. ANTHONY.
